Arthur C. Kleckner
William Bradbury
McLabb & Bradbury Atlys.

UNITED STATES PATENT OFFICE.

ARTHUR C. KLECKNER, OF RACINE, WISCONSIN, ASSIGNOR TO WEBSTER ELECTRIC COMPANY, OF RACINE, WISCONSIN, A CORPORATION OF WISCONSIN.

MAGNETO.

Application filed March 10, 1924. Serial No. 698,062.

This invention relates to magnetos of the type in which the driven member carrying the rotor is intermittently held and released to produce the spark when the magneto 5 driving shaft is being rotated slowly, but upon rapid rotation of the driving shaft the driven shaft moves continuously therewith.

The object of the invention is to provide a magneto of this type in which the centrifugal means which acts to render the impulse mechanism inoperative is carried on the constantly rotating driving shaft, thus rendering the operation of the mechanism more certain than is the case when the centrifugal means is carried on the driven member, as has heretofore commonly been the practice.

It is believed the invention will be understood most readily from a detailed description thereof taken in connection with the accompanying drawings, in which

Figure 1 is a sectional view through one end of the magneto shaft and parts adjacent thereto;

Figure 2 is a section substantially on the line 2—2 of Figure 1;

Figure 3 is a section substantially on the line 3—3 of Figure 1;

Figure 4 is a view of the impulse mechanism looking at the device of Figure 4 from above and to the right;

Figure 5 is a view similar to Figure 1 through a modified form of the invention, and

Figure 6 is a section substantially on the line 6—6 of Figure 5.

Referring now to the drawings, in which like reference characters indicate the same parts in the several views, 10 indicates the 40 end plate of the magneto which carries the bearing 11. Rotatably mounted in the bearing 11 is the driving shaft 12 upon which is fixed the gear 13 by means of which the shaft is continuously rotated when the device is in operation.

At 14 are shown portions of the rotor which are fixed to the driven shaft 15. The shaft 12 is hollow throughout the greater portion of its length, and the reduced end 16 of shaft 15 projects into the bore of shaft 12. Fixed to the left end of the shaft 12, as seen in Figure 1, is the disc 17 provided with the substantially cylindrical flange 18. Fixed to shaft 15 is the disc 19 having the cylindrical flange 20. Positioned between the

flanges 18 and 20 is the spiral spring 21, one end of which is secured to flange 18, the other being secured to flange 20. Stamped out of the disc 19 is the laterally directed lug 22 which extends into the path of the lug 23 which is pressed out of the disc 17. The lugs 22 and 23 are adapted to limit relative movement in one direction of the discs 17 and 19, the spring 21 being normally under tension so as firmly to maintain said lugs 22 and 23 in engagement.

Pivottally mounted on the periphery of the flange 20, by means of the pivot 24, is the dog 25 provided with the upwardly extending flange 26. Pivottally mounted on the fixed pin 27 carried by the magneto frame is a pawl 28 which is normally pressed downwardly by means of the spring 29, downward movement of the pawl being limited by engagement with the shoulder 30.

A spring 31 is fixed to the periphery of the flange 20 and normally tends to rotate the dog 25 in a clockwise direction, as viewed in Figure 4.

Loosely mounted about the shaft 12 is a spider 32 which carries the annular disc 33. The free edge of the flange 18 is joined to the annular disc 33 by means of the links 34, one end of each link 34 being pivoted on a pin 35 carried by lugs 36 struck out of the annular disc 33, the other end of each link 34 being pivottally supported on a pin 37 carried in the lugs 38 struck out of the edge of the cylindrical flange 18.

Fixed to the links 34 are the centrifugal weights 40 which are adapted to move outwardly upon rapid rotation of the shaft 12 and force the annular disc 33 to the left, as viewed in Figures 1 and 4. A coil compression spring 41 is provided between the spider 32 and the disc 17 which normally tends to move the spider 32 and annular disc 33 to the right, as seen in Figure 1. The annular disc 33 is provided with a laterally extending lug 42.

The operation of the device is as follows:

The spring 31 will normally maintain the dog 25 in a position such that the upwardly extending lug 26 carried by the dog will travel a path to bring it into engagement with the end of pawl 28. This will act momentarily to stop the rotation of the driven shaft 15, but will permit the continued rotation of shaft 12. Further rotation of the shaft 12 will bring the lug 42 carried by the

annular disc 33 into engagement with the cam on the right side of dog 25, as seen in Figure 4, moving the dog about its pivot 24 and causing the lug 26 to become disengaged from the pawl 28. The spring 21 will thereupon operate quickly to snap the rotor element of the magneto forwardly until the lug 22 engages the lug or finger 23. This operation in the form of the device shown in Figures 1 to 4 will take place once for every revolution of the shaft 12.

When, however, the shaft 12 is rotated rapidly the weights 40 will move outwardly due to centrifugal force, and will force the spider 32 and disc 33 to the left against the tension of the spring 41. As the disc 33 moves to the left, as viewed in Figure 1, it will engage the edge of the dog 25 and will rotate the dog about its pivot 24, thus moving the upwardly extending portion 26 out of the path of the pawl 28. The tension in the spring 21 will now maintain the lug 22 firmly in engagement with the finger 23 and the driving and driven shafts will rotate together. When, however, the speed of rotation of shaft 12 slows down, the disc 33 will be moved to the right by the spring 41 and the magneto will again act as an impulse starter.

The device shown in Figures 5 and 6 is the same in operation as that shown in Figures 1 to 4 except the centrifugal devices are rotatable about axes parallel to the shaft instead of about axes at right angles to the shaft. In the form of device shown in Figures 5 and 6, there is secured to the driving shaft 12 a disc 60 to which the centrifugal levers 61 are pivotally joined through the medium of pins 62. Slidably, but non-rotatably, mounted on the shaft 12 is a collar 63 having the outwardly extending flange 64. The flange 64 is provided with a cam surface 65 adapted to be engaged by cams 66 carried by the levers 61. A spring 67 is provided between the disc 60 fixed to the driving shaft and the flange 64, which normally tends to keep flange 64 to the right, as seen in Figure 5.

The operation of the device of Figures 5 and 6 is the same as that previously described, the sole difference residing in the centrifugal apparatus for actuating the disc 64 which corresponds with the disc 33 of Figure 1.

In impulse starters of the type commonly employed heretofore, the centrifugal apparatus has been mounted on the driven member. Due to the fact that the driven member was rotated intermittently through the stop and start mechanism, the operation of the centrifugal means was oftentimes rendered uncertain. In the present device, the centrifugal means being mounted on the constantly rotating driving member, the uncertainty of operation which was objection-

able in the type of impulse starter just referred to is obviated.

While in the drawings and in the above description, applicant has limited his disclosure to certain definite details, it is to be understood that many modifications are contemplated and the invention should, therefore, be limited merely by the scope of the appended claims.

Having thus described my invention, what I claim as new and desire to secure by Letters Patent of the United States is:

1. In a magneto, a driven member, a driving member, resilient means joining said members, means pivotally mounted on said driven member for restraining the movement of said driven member, means carried by said driving member for intermittently releasing said restraining means, and centrifugal means carried by said driving member for rendering said restraining means inoperative whereby said members are driven continuously together.

2. In a magneto, a driving shaft, a driven shaft, a spring joining said shafts whereby said shafts tend to rotate together, means for restraining the movement of said driven shaft, means carried by said driving shaft for intermittently releasing said restraining means, and centrifugally operated means carried by said driving shaft and movable axially thereof for rendering said restraining means inoperative whereby said shafts are driven continuously together.

3. In a magneto, a driving shaft, a driven shaft, a spring joining said shafts whereby they tend to rotate together, a fixed abutment, a dog carried by said driven shaft arranged to engage said abutment to momentarily prevent rotation of said driven shaft, means carried by said driving shaft for moving said dog out of engagement with said abutment, and means carried by said driving shaft for preventing engagement of said dog with said abutment whereby said shafts rotate substantially in unison.

4. In a magneto, a driving shaft, a driven shaft, a spring joining said shafts whereby they tend to rotate together, a fixed abutment, a flange fixed to said driven shaft, a dog pivotally joined to said flange and normally arranged to engage said abutment, a disc rotatable with said driving shaft, means carried by said disc for disengaging said dog from said abutment, and centrifugal means for moving said disc laterally whereby said dog is displaced so as to prevent engagement thereof with said abutment.

5. In a magneto, a driving shaft, a driven shaft, a spring joining said shafts whereby they tend to rotate together, a cylindrical flange fixed to said driven shaft, a dog pivotally supported on the periphery of said flange, a fixed abutment arranged to

be engaged by said dog whereby the rotation of said driven shaft is momentarily prevented, a disc rotatable with said driving shaft, means carried by said disc for 5 intermittently disengaging said dog from said abutment, and centrifugal means carried by said driving shaft for moving said disc laterally whereby it engages said dog and maintains it out of engagement with 10 said abutment to permit said shafts to be rotated in unison.

6. In a magneto, a driven member, a driving member, resilient means joining said members, a stop, a dog carried by said driving member arranged to engage said stop, means carried by said driving member for 15 moving said dog relative to said driven member for disengaging the same, and centrifugal means carried by said driving member for preventing engagement of said dog with said stop whereby said driving and driven members rotate substantially in unison.

7. In a magneto, a driven member, a driving member, resilient means joining said members, an abutment, a dog pivotally mounted on said driven member and adapted 25 for engagement with said abutment, means carried by said driving member for intermittently releasing said dog, and separate centrifugal means carried by one of 30

said members for rendering said dog inoperative whereby said members are driven continuously together.

8. In a magneto, a driven member, a driving member, resilient means joining said members, an abutment, a dog pivotally mounted on said driven member and adapted for engagement with said abutment, means 35 associated with said driving member for intermittently pivoting said dog out of engagement with said abutment, and centrifugally operated means carried by said driving member and movable axially thereof for holding said dog out of the path of 40 said abutment.

9. In a magneto, a driven member, a driving member, a spiral spring coiled axially of said members for connecting the same, means for restraining the movement of said driven member, means carried by said driving member for intermittently releasing said restraining means, and centrifugal means carried by said driving member for rendering said restraining means inoperative 50 whereby said members are driven continuously together.

In witness whereof, I hereunto subscribe my name this 19th day of February, 1924.

ARTHUR C. KLECKNER.
